BROKEN AXLE SHAFT REMOVER

Filed July 16, 1931

Inventor

H. R. Jarvis

By Watson E. Coleman

Attorney

UNITED STATES PATENT OFFICE

HAROLD R. JARVIS, OF RIVES JUNCTION, MICHIGAN

BROKEN AXLE SHAFT REMOVER

Application filed July 16, 1931. Serial No. 551,257.

This invention relates to means for removing broken axles or the like from their housings.

An object of this invention is to provide means which may be inserted in a hollow or elongated tubular housing for removing broken axles or other members from the housing.

A further object of this invention is to provide a clamping device of this kind which is so constructed that it can be readily clamped about an article disposed within a tubular element for removing the article.

A still further object of this invention is to provide a device of this kind which is exceedingly simple in construction so that the device may be readily and cheaply manufactured.

The above and various other objects and advantages of this invention will in part be described in and in part be understood from the following detailed description of the present preferred embodiment, the same being illustrated in the accompanying drawing wherein:—

Figure 1 is a fragmentary longitudinal section partly in detail of a device constructed according to the preferred embodiment of this invention;

Figure 2 is a fragmentary detail side elevation of the device, and

Figure 3 is a sectional view partly in detail taken on the line 3—3 of Figure 1.

Referring to the drawing wherein like numerals of reference designate corresponding parts throughout the several views, the numeral 10 designates generally an elongated bar or shaft which is provided with a threaded portion 11 extending inwardly from one end thereof, and the numeral 12 designates a sleeve or tubular element which is loosely mounted about the periphery of the bar or rod 10, and which threadably engages the threads 11 so that rotation of the sleeve or tube 12 will move the tube longitudinally of the rod 10.

This rod 10 at one end thereof is provided with pairs of opposed arms 14 which are formed integrally with the bar 10 and are disposed in an outwardly flaring or divergent

position and the outer surface of these arms 14 is also provided with threads forming a continuation of the threads 11 so that longitudinal movement of the sleeve 12 will force the arms 14 one toward the other into clamping position. The outer ends of these arms 14 are bent inwardly, as at 15, so as to provide clamping members which have a pair of prongs 16 formed therewith, these prongs being of V-shaped construction so as to readily engage about the periphery of a round object in the form of a shaft or the like.

In normal position, these clamping members 15 are disposed away from each other so that the end of a shaft or other object may be readily inserted between these clamping members 15 and upon longitudinal movement of the sleeve 12, the arms 14 will be drawn together and coercively the clamping members 15 will be drawn toward each other and into engagement with the object disposed therebetween.

Preferably, the prongs 16 are suitably hardened or tempered so that the points of the prongs will readily grip a metal object and firmly hold the object therebetween. A sleeve operating member or lever 17, which has a bifurcated end portion 18 and alined lugs 19 is mounted in alined apertures 20 disposed in the sleeve 12 adjacent the inner end thereof. Preferably, the bifurcated portion 18 of the sleeve operating member 17 is bent angularly with respect to the longitudinal axis of the body of the operating member 17 so that this operating member can be readily disposed in inoperative position closely adjacent the periphery of the sleeve 12. In this folded position, the device will occupy only a relatively small space.

The inner end portion of the rod 10 is provided with an aperture 13 diametrically therethrough which may be engaged by a cable or other flexible element so that extra pressure may be applied for pulling the article out of the housing from which the shaft or other element is being withdrawn. If desired, the bar 10 may be of hollow construction so as to make the device relatively light in weight and also to facilitate the construc-

tion of the divergent arms 14 which are integrally formed therewith.

In the use of this device, the sleeve 12 is rotated about the bar or body member 10 so that the clamping arms 14 will be in a position to readily be inserted into the desired housing or element from which the article is adapted to be removed and the clamping members 15 will be disposed apart sufficiently that they may be inserted about the article within the housing or other hollow element. When the prongs 16 are disposed about the shaft or other element, the sleeve 12 may be rotated by means of the sleeve operating member 17, thereby moving the sleeve 12 inwardly of the housing and forcing the divergent arms 14 inwardly and co-actively clamping the clamping elements 15 about the shaft or other article. When the clamping members 15 are tightly engaged with the shaft or article, the entire device may be pulled outwardly of the housing either by manually withdrawing the device, or a cable or other element may be attached to the inner member 10 in the aperture 13 and the desired pressure applied thereto so as to pull the shaft from the housing.

It is, of course, understood that various changes and modifications may be made in the details of construction and design of the above specifically described embodiment of this invention without departing from the spirit thereof, such changes and modifications being restricted only by the scope of the following claims.

I claim:—

1. A puller of the character described comprising divergent opposed clamping arms connected together at one end, threads formed on the outer surface of each of said arms, a threaded tubular element engaging the threaded portions of each of said arms whereby upon rotation of said tubular element the arms will be drawn one toward another for clamping an article therebetween, and means for rotating said tubular element.

2. A puller of the character described comprising divergent yieldable opposed clamping arms secured together at one end thereof, an elongated round element formed with the inner ends of said arms, threads carried by the outer surface of said arms, a tightening member engaging the threads of said arms and adapted upon rotation thereof in one direction to force said arms inwardly one toward another whereby to releasably clamp an article therebetween, and an operating member swingably carried by said tightening member.

3. A puller of the character described comprising pairs of divergent clamping arms, an elongated bar formed with the inner end of each arm, a tubular member disposed about said bar and having a threaded outer end portion engaging the threads on said arms, and

operating means carried by said tubular member whereby to rotate said tubular member for movement of said arms into clamping or released position.

4. A puller of the character described comprising divergent yieldable clamping arms, an elongated bar formed with the inner ends of the arms, clamping members carried by the divergent ends of said arms, threads disposed on the outer surface of the arms, a threaded sleeve disposed about the bar and threadably engaging said arms whereby upon movement of the sleeve in one direction the arms will be forced inwardly one toward another, and an operating lever carried by the inner end of said sleeve whereby to facilitate rotation thereof.

5. A puller of the character described comprising divergent clamping arms of yieldable construction, an elongated bar formed with the inner end of the arms, clamping members formed with the divergent outer ends of the arms, said clamping members including spaced prongs carried by each of said members, threads formed on the outer surface of each of said arms, an elongated sleeve having a threaded outer end portion adapted to threadably engage the threaded outer surface of said arms, and a pivoted operating member carried by the inner end of said sleeve whereby to facilitate rotation thereof about said bar and about said arms for movement thereof into clamping or released position.

In testimony whereof I hereunto affix my signature.

HAROLD R. JARVIS.
